UNITED STATES PATENT OFFICE.

GEORGE L. LUDWIG, OF MILWAUKEE, WISCONSIN, ASSIGNOR TO MOE-BRIDGES COMPANY, OF MILWAUKEE, WISCONSIN, A CORPORATION OF WISCONSIN.

DESIGN FOR A LAMP BASE.

Application filed May 12, 1922. Serial No. 2,209. Term of patent 3½ years.

To all whom it may concern:

Be it known that I, GEORGE L. LUDWIG, a citizen of the United States, residing at Milwaukee, in the county of Milwaukee and State of Wisconsin, have invented a new, original, and ornamental Design for Lamp Base, of which the following is a specification, reference being had to the accompanying drawings, wherein—

Fig. 1 is a side elevation,

Fig. 2 is a plan view, and

Fig. 3 is a detail plan view showing the pedestal of the lamp base with the body portion thereof removed.

I claim as my invention:

The ornamental design for a lamp base, as shown.

GEORGE L. LUDWIG.
